UNITED STATES PATENT OFFICE.

ROSCOE R. STITT, OF DETROIT, MICHIGAN, ASSIGNOR TO STITT REFRIGERATION COMPANY, OF DETROIT, MICHIGAN, A CORPORATION OF MICHIGAN.

REFRIGERATING APPARATUS.

Application filed May 1, 1924. Serial No. 710,229.

This invention relates to a refrigerator apparatus and more particularly pertains to the assembly of the parts whereby a more efficient operation of the machine is had.

- 5 It is the object of the present invention to assemble the condenser in such a way that a fan may be mounted and driven for directing air currents in two directions, for cooling the condensing coils and the compressor. 10 This arrangement of parts results in an easy assembly as a unit so that the same may utilize a minimum amount of floor area. This is a highly important item, because where the refrigerating apparatus is used in small 15 apartments or flats the question of space is a determining factor. Also my arrangement has a decided advantage of more efficiently cooling the working parts and houses the fan which ordinarily rotates at high speed to 20 prevent anyone from accidentally getting in the way of the revolving blades.

In the drawings:

Fig. 1 is an elevational view of my refrigerating apparatus.

- 25 Fig. 2 is a section on the line 2—2 of Fig. 1, showing the condenser and the fan housed therein.

Fig. 3 is an enlarged detailed sectional view showing the condenser construction.

- 30 C designates the compressor which may be of a standard construction, although I have here shown a compressor described and claimed in my copending application Serial No. 710,230. The source of power here shown 35 is a motor M, which is adapted to be driven and is connected up with the compressor so as to operate the same. The motor drive shaft a, is connected to the crank shaft b of the compressor through a suitable speed reducer c. However, the position of this speed 40 reducer is immaterial and if the source of power were at a distant point and transmitting to the compressor through a belt drive, it would not be necessary to incorporate a 45 speed reducer in the apparatus. I locate a condenser, designated as a whole as d, between the source of power and the compressor. This condenser consists of a top header e and a lower header f, and the semi-circular pipes g connect the upper and lower 50 headers. The spiral fins h are soldered or otherwise secured to the pipes g, which serve as the condensing coils. The purpose of these fins is to provide a large area for cooling purposes. As shown in Fig. 2, the condenser is

concentrically arranged about the motor drive shaft a and secured to the shaft is the fan k, which as shown in Fig. 1 is completely housed by the condensing coils of the condenser. This will prevent anyone from accidentally coming in contact with the fan which rotates at a high velocity. The blades of the fan are inclined slightly but they direct the larger portion of the air currents radially past the condensing coils, and the 60 remaining portion of the air is directed transversely to the first mentioned air currents and directed onto the compressor housing. In this way the fan serves a double purpose in that it directs air currents onto the condensing coils and onto the compressor directly. 65

Such an assembly of the fan and condenser has a big advantage over the ordinary assembly as the air currents directed to the compressor coils strike directly against the same and the whole coil surface is exposed to the cooling air currents directed thereon. In addition, the fan directs an independent current of air against the compressor so that the 70 compressor is cooled directly and not indirectly as is the case with the usual construction which blows the air first against the condenser and then against the compressor. 75

In Fig. 1 a complete circulating path of the 80 refrigerating system is seen wherein the compressed gas is forced through the exhaust port of the compressor into the conduit m, into the top header of the condenser where it is condensed into a liquid. This cooling liquid or 85 refrigerant is then conducted to the refrigerator n through the conduit o, where it absorbs heat and becomes gasified and is then conducted back to the compressor through the conduit p. 90

95 What I claim is:

1. In a refrigerating apparatus, the combination of a compressor, a source of power, means for connecting a compressor in driving relation with the source of power, said compressor being positioned adjacent said source of power, a condenser positioned between said compressor and source of power to thereby form a compact unit, and a fan positioned within the said condenser having 100 blades arranged to direct two separate cooling air currents, one radially and directly against the condenser and the other transversely to the radial air currents, and directly onto the compressor. 105

2. In a refrigerating apparatus, the combination of a compressor unit, condenser coils forming a condenser unit and a single means for creating and directing a current of air in one direction towards the compressor unit, and a second and separate current of air in another direction towards the condenser unit.
3. In a refrigerating apparatus, the combination of a motor, a compressor and condenser coils all compactly arranged with the condenser coils disposed between the motor and compressor to form a compact assembly,

and a fan on the motor shaft which lies within and which is housed by the said condenser coils, said fan having radially extending blades which throw a current of air radially outward over the condenser coils to cool the same, said blades being inclined to throw an air current axially and directly against the compressor to cool the compressor. 15

In testimony whereof I have affixed my signature. 20
